UNITED STATES PATENT OFFICE.

THOMAS G. BOWERS, OF NEW HAVEN, CONNECTICUT.

CORSET.

Application filed February 19, 1921. Serial No. 446,392.

To all whom it may concern:

Be it known that I, THOMAS G. BOWERS, a citizen of the United States, residing in New Haven, county of New Haven, State of Connecticut, have invented certain new and useful Improvements in Corsets, of which the following is a full, clear, and exact description.

This invention relates to corsets and more particularly to a corset which is provided with an abdominal or other support to which straps are adapted to be attached to retain this support in position. These straps are, in the form of my invention which I have chosen to illustrate and describe, arranged to pass through slots which are formed in the corset body, so that they may be buckled upon the outside of the corset and thereby may be conveniently accessible to buckle and release. The improvements which I have made particularly deal with this support and with that part of the corset which is arranged to permit the straps to pass therethrough.

One object of my invention is to provide an improved method of manufacture of a corset of the character described.

A further object of the invention is the provision of a corset of this type which will be strongly made and will be durable and one in which the slots which are formed to receive the straps will not be inclined to tear.

A further object of my invention is to provide a corset of the class described with slots through which the straps which are attached to the abdominal support may pass without appreciably weakening the body of the corset.

A still further object of the invention is to provide improved reenforcing means for a corset and to generally improve the structure of the corset so that the same will have wear resisting qualities, will be comfortable when adjusted and will be of improved quality generally.

To these and other ends the invention consists in the novel features and combinations of parts to be hereinafter described and claimed.

In the accompanying drawing:

Fig. 1 is a side elevational view of a corset embodying my improvements;

Fig. 2 is a view similar to Fig. 1, but showing the corset unfastened to disclose the abdominal support;

Fig. 3 is an enlarged detail view of that portion of the corset which is slotted to receive the straps attached to the abdominal support;

Fig. 4 is a sectional view on line 4—4 of Fig. 3; and

Fig. 5 is an enlarged detailed sectional view taken substantially on line 4—4 of Fig. 3, but having some parts omitted for the sake of clearness.

While I have shown my improvements as applied to a front laced corset, it is to be understood that they may be applied to other corsets as well without departing from the scope of the invention.

The corset consists of a main body portion 10, which is as shown laced at 11 and provided with clasps or other fastening means at 12 where the two edges of the body meet.

The corset is provided with an abdominal support 13, which is formed in two parts 13^a and 13^b, which meet and are clasped together at 13^c, as shown in Fig. 2. The abdominal support extends across the front portion of the corset and at each end thereof is provided with a plurality of straps 14, which pass through the corset at the sides thereof and are secured in buckles 15, which are mounted upon the outside of the corset body.

The front portion of the corset consists of two gores 16 and 17, which are separate from the back 18 of the corset and are joined thereto along the lines 19 and 20. The particular manner in which these gores are joined to the back portion of the corset enables me to provide an improved form of slot through which the straps are passed from the inside to the outside of the same and is a very important feature in strengthening this portion of the article. The edges of the back portion of the corset are turned over and stitched, as shown at 21 in Fig. 5, and a facing strip 22 is applied thereto. The gores 16 and 17 are provided with substantially V-shaped reenforcing strips 23 and 24, which, as shown more particularly in Fig. 3 extend from the rear edge of the gore to the front edge or the clasp portion of the same. The reenforcing strip 23 extends from the rear edge of the gore to the front edge of the same. The rear edges of the gores 23 and 24 are turned and stitched, as shown at 25, and a facing strip 26 is applied thereto in the same manner, as previously de-

scribed. The gores 16 and 17 are provided with substantially V-shaped reenforcing strips 23 and 24, which, as shown more particularly in Fig. 3 extend from the rear edge of the gore to the front edge or the clasp portion of the same. The reenforcing strip 23 extends from the rear edge of the gore to the front edge of the same. The rear edges of the gores 23 and 24 are turned and stitched, as shown at 25, and a facing strip 26 is applied thereto in the same manner, as previously de-

scribed in connection with the front edge of the back portion of the corset, which is turned at 21.

The front edges of the back portion of the 5 corset, as clearly shown in Fig. 5, are made to overlap the rear of the gores 16 and 17, so that the stitched turned-over portion of the back part of the corset may be sewed upon the stitched turned-over edge of the 10 gores. These overlapping edges are stitched continuously from the upper and lower edges of the corset to that portion where it is desired to provide the slots 27 through which the straps 14 are adapted to pass. 15 The edges here are sewed only at intervals, such as at the points 28, to provide the slots 27 between these sewed portions to permit the passage of the straps. The V-shaped reinforcing strip 24, it will be noted, is applied to that part of the corset in which the 20 slots 27 are provided and where the meeting edges of the back part and front gores of the corset are not continuously stitched. This, it is noted, will serve to strengthen this part 25 of the corset, which otherwise might have a tendency to be weakened by the provision of the slots 27, where the front gores are not stitched or sewed to the back part of the corset.

30 A tape 29 is secured upon each of the front gores 16 and 17 of the corset, which tape is sewed at points 30 along its length to provide the slots 31 which act as keepers for the loose ends of the straps 14.

35 A reenforcing piece 32 is formed upon each side of the back portion of the corset and the tapes 33 by which the buckles 15 are secured to the corset are fastened beneath these strips 32. It will be seen that 40 this will provide a strengthening rib to take the pull upon the buckles 15 exerted by the straps 14 attached to the abdominal pad. This strip 32 is secured to one of the stay seams 34, so that the pull upon the straps 45 will come upon one of the strong stay seams. It will be understood that one of the strips 32 is provided upon each side of the corset in connection with each set of buckles 15.

While I have shown and described a preferred embodiment of my invention, it will be understood that the same is not to be restricted thereto in all of its details, but is capable of many modifications and variations, which will lie within the spirit of the 50 invention and within the scope of the appended claims.

It will be obvious that while my improvements are shown in connection with a corset having an abdominal support or front pad, the invention may well be applicable to 60 corsets of other types, for instance, to one having a pad at the rear portion thereof. In such case, the slots 27 might be arranged to open or face forwardly instead of rearwardly, as shown. I do not intend, therefore, to limit myself to the construction shown wherein the front pad or abdominal support is used.

What I claim is:

1. A corset comprising a plurality of sections, the meeting edges of two thereof being arranged to overlap, and sewed together at spaced points only for a portion of their length, to provide a plurality of slots, a strip 70 stitched to one of said sections to reinforce the same, and sewed therewith at said spaced points to the other section, and extending to the opposite edge of the first section, corset fastening devices secured to said opposite edge of the first section, a plurality 75 of buckles secured to the second section adjacent said slots, an abdominal support adapted to be worn beneath the corset and having straps connected to its ends, said straps being passed through said slots and secured to 80 said buckles, and means for reinforcing the garment at the points at which said buckles are connected thereto.

2. A corset including a front section and a rear section, said sections being joined at 90 the side of the garment by having their edges overlapped and sewed continuously together for a portion of their length and at spaced points, only, for another portion of their length, to provide a plurality of slots, a strip 95 stitched to the front section to reinforce the same, said strip embracing the said slotted portion of the two sections, being sewed to both sections at said spaced points, and extending to the opposite edge of the front 100 section, corset fastening devices secured to said opposite edge of the front section, a plurality of tapes secured to the rear section of the corset adjacent said slots, a reinforcing strip secured to the garment over said tapes, 105 buckles upon the ends of the tapes, an abdominal support adapted to be worn within the corset, and straps secured to said support and connected to said buckles.

In witness whereof, I have hereunto set 110 my hand this 17th day of February, 1921.

THOMAS G. BOWERS.
